UNITED STATES PATENT OFFICE

WILLIAM J. CIPRA, OF CLEVELAND, OHIO

NOISE PRODUCING TOY

Application filed January 29, 1931. Serial No. 512,139.

This invention relates to games and toys and more particularly to a device adapted to be hand operated and by means of which loud noises may be produced.

6 One object of the invention is to provide a noise producing device which is very simple in construction and easy to operate and by means of which loud clattering noises may be produced. The device is particularly intended for use during carnivals, during ball games between opposing schools and at other times when participants or an audience desires to make noises.

15 Another object of the invention is to provide a device of this character including telescoping sections which are to be forced towards each other and will be yieldably held against such movement; thereby causing them to return to an extended position and permitting the device to be very easily operated.

Another object of the invention is to so form one of the telescoping sections that the volume of noise produced may be controlled when the device is in use.

25 The improved noise producing device is illustrated in the accompanying drawings, wherein

Figure 1 is a perspective view of the improved device, and

30 Figure 2 is a longitudinal sectional view through the same.

This improved noise producing device consists of companion sections 1 and 2 which have telescoping engagement with each other and are to be slid longitudinally when the device is in use.

The outer section 2 has a tubular body 3 which fits about the body 4 of the section 1 and has a head 5 at its outer end, the marginal portions of which are clamped to the walls of the body as shown at 6.

The section 1 is hollow and has at its inner end a head 7 which may be formed integral with the walls of the body or firmly secured thereto in any desired manner.

There has also been provided a head 8 for the outer end of the inner section. This head is formed separate from the body portion of the outer section and may be soldered or otherwise firmly secured thereto or be

formed with a marginal rim 9 which is threaded upon the walls 4 as shown at 10 or firmly but detachably secured in any other desired manner. This outer head is perforated as shown at 11 so that sound waves may pass outwardly from the inner section when the device is in use.

In order to control sliding movement of the two sections relative to each other and produce noises when the device is in use, there has been provided a roughened rod 12 which is preferably in the form of a threaded bolt of a desired length and thickness. This bolt is passed through an opening formed in the center of a head 5 with its head 13 bearing against the outer face of the head 5, and upon the bolt are applied securing nuts 14, which when tightened will cause the head of the outer section to be firmly gripped and the bolt held firmly in place in axial relation to the two sections.

An opening 15 is formed centrally through the inner head 7 of the inner section and while this opening is of sufficient size to permit the rod or bolt to pass through it, it will be sufficiently small to cause the threads of the bolt to have contacting engagement with the head 7 of the inner section and cause noises to be produced when the two sections are slide longitudinally of each other. A nut 16 which is threaded upon the free end portion of the bolt serves to engage the inner head 7 of the inner section and limit sliding movement of the two sections away from each other. A coil spring 17 which is disposed in the outer section and confined between the head 5 thereof and the inner head 7 of the inner section yieldably resists inward movement of the inner section and serves to move the two sections away from each other after they have been pressed towards each other.

When this device is in use, it is held by the hands and pressure applied longitudinally of the sections to force the two sections towards each other. Pressure is then released and the spring will move the sections apart until such movement is stopped by engagement of the nut 16 with the inner head of the inner section. The two sections may be formed entirely of metal or only the head 7

of the inner section formed of metal. Since this head 7 is formed of metal, engagement of the threads of the bolt 12 with the margins of the opening 15 will cause loud noises to be produced when the two sections are slid longitudinally of each other. By partially or entirely covering the head 8 with the palm of one hand, the volume of noise may be reduced a desired amount. It will thus be seen that the volume may be controlled.

10 What is claimed is:

1. A sound producing device comprising companion sections telescoping one within the other, a roughened shaft extending longitudinally of the outer section, the inner section being provided with a disk formed with an opening slidably receiving the shaft, the disk constituting a noise producing element actuated by contact with roughened portions of the shaft when the two sections are moved longitudinally of each other.

2. A sound producing device comprising companion sections telescoping one within the other, and a threaded shaft extending longitudinally in the outer section, the inner section being provided with a disk formed with an opening snugly receiving the shaft whereby the shaft may pass through the disk with its threads engaging the disk to produce noise when the sections are slid longitudinally of each other.

3. A sound producing device comprising companion sections telescoping one within the other, and a threaded shaft extending longitudinally in the outer section, the inner section being provided with a disk formed with an opening snugly receiving the shaft whereby the shaft may pass through the disk with its threads engaging the disk to produce noise when the sections are slid longitudinally of each other, and a spring yieldably resisting inward movement of the inner section.

4. A sound producing device comprising companion sections telescoping one within the other, and a threaded shaft extending longitudinally in the outer section, the inner section being provided with a disk formed with an opening snugly receiving the shaft whereby the shaft may pass through the disk with its threads engaging the disk to produce noise when the sections are slid longitudinally of each other, and a head for the outer end of the inner section, the head being perforated whereby sound waves may pass out of the inner section and the volume of sound controlled by placing a hand over the perforated head.

5. A sound producing device comprising companion sections telescoping one within the other, the inner section having heads for its inner and outer ends and the outer section having a head for its outer end, a threaded rod extending longitudinally in the outer section with its outer end fixed to the head of the outer section, the inner head of the inner

section being formed with an opening snugly receiving the rod whereby the threads of the rod may act upon the inner head to create noise when the sections are moved longitudinally of each other, means to limit movement of the sections away from each other, and means to yieldably resist movement of the sections towards each other.

6. A sound producing device comprising companion sections telescoping one within the other, the inner section having heads for its inner and outer ends and the outer section having a head for its outer end, a threaded rod extending longitudinally in the outer section with its outer end fixed to the head of the outer section, the inner head of the inner section being formed with an opening snugly receiving the rod whereby the threads of the rod may act upon the inner head to create noise when the sections are moved longitudinally of each other, a nut upon the inner end portion of said rod to engage the inner head of the inner section and limit movement of the sections away from each other, and a spring in the outer section bearing against its head and the inner head of the inner section and serving to yieldably resist movement of the sections towards each other, the outer head of the inner section being perforated whereby sound waves may pass out of the inner section and the volume of sound controlled by placing a hand over the perforated head.

7. A sound producing device comprising companion sections telescoping one within the other, a roughened shaft extending longitudinally of the outer section, the inner section being provided with an element formed with an opening slidably receiving the shaft, the said element constituting a noise producing means actuated by contact with roughened portions of the shaft when the two sections are moved longitudinally of each other.

In testimony whereof I affix my signature.
